STICK MOUNTED WINDMILL

Marvin Katz, Brooklyn, N.Y., assignor to Kaye Novelty Co., Inc., Brooklyn, N.Y., a corporation of New York

Filed July 12, 1963, Ser. No. 75,775

Term of patent 14 years

(Cl. D34—15)

FIG. 2

FIG. 1 is a top plan view of a stick mounted windmill embodying my new design, and

FIG. 2 is a front elevational view thereof.

I claim:

The ornamental design for a stick mounted windmill, as shown.
